UNITED STATES PATENT OFFICE.

HARLEY BROOMHALL, OF SHELBY, OHIO, ASSIGNOR TO THE SHELBY METAL PRODUCTS COMPANY, OF SHELBY, OHIO, A CORPORATION OF OHIO.

OPERATING MECHANISM FOR DOOR LATCHES.

Application filed April 14, 1926. Serial No. 101,901.

This invention relates to improvements in an operating mechanism for a door latch.

One of the objects of the present invention is to provide a latch that can be operated in either direction from its normal yieldingly locked position and by means of the use of one expansible coil spring returned to its normal position when the lever is released.

10 Another object of the present invention is to provide a U-shaped cam member which is adapted to contact with a sliding latch member and is adapted to press against the sliding latch under tension of a coil spring to open a door, the latch being operable in either direction from both sides of the latch body by manipulation of a lever, or a door knob.

Another object is to provide means on the 20 U-shaped cam member to connect it to a door knob shaft for actuation of the latch mechanism and by means of the connection provide means to shorten the length of the shaft required for the purpose intended.

25 Another object is to form a sliding latch member with a portion thereof bent at right angles to the body portion to contact with or provide an abutment for a coil spring and support one end of a coil spring pin support.

Another object of the invention is to construct a latch mechanism and its associated parts of pressed sheet metal so as to provide a latch mechanism of light weight and comparative maximum strength, free from the defects incident to casting the parts and also to provide surfaces that admit of making a latch mechanism of smooth finish interiorly and exteriorly.

40 A further object is to hold and maintain the latch and its associated mechanism in operating positions without the use of a cover plate.

Another object is to provide unit means 45 for exerting a pressure on the latch mechanism.

These and other objects are attained by the mechanism illustrated in the accompanying drawing in which:

50 Figure 1 is an elevation of the latch mechanism assembled in the body.

Figure 2 is a similar view, the latching mechanism being omitted.

Figure 3 is an end view of Figure 1.

Figure 4 is a cross sectional view of Figure 55 1 on the line 1—1.

Figure 5 is an elevation of the sliding latch member.

Figure 6 is a side view of Figure 5.

Figure 7 is an elevation of the U-shaped 60 cam member.

Figure 8 is a top view of the U-shaped cam member.

Figure 9 is an elevation showing the latch mechanism retracted from its normal position by the operation of the lever in both directions and also showing in full lines the latch in its normal or yielding locked position.

In the construction and assembly of the 70 sheet metal parts to attain the objects set forth, a hollow body is pressed from sheet metal or the like and comprises a body portion 1, upstanding side portions 2—2¹ (preferably rectangular in form) and extending 75 flanged portions 3—3 are formed thereon, and provided with apertures 4 to receive suitable screws or the like to fasten the body portion to a door or the like. An aperture 3¹ is provided in the body portion 1 and is 80 surrounded by an integral rib 5.

A slot 6 preferably formed square is provided in one of the sides 2¹ as shown in Figure 4. A sliding latch member 7 is provided made of sheet metal or the like, and 85 has integral portions 8 and 9 turned up at right angles to the body portion 7. The latch member 7 is also provided with longitudinal slot 7', which allows the latch member to slide back and forth in the hollow body. A latch 10 is formed integral with the body portion 7 and is adapted to slide into the slot 6 and normally extends beyond the side 2¹ in yieldingly locked position, when associated with a conventional 90 strike or the like.

The latch 10 is yieldingly held in locked position as follows:

One end of a pin 11 is supported in an aperture provided in the side 2 of the body 100 and its opposite end is supported in an aperture provided in the upturned portion 8 of the sliding member. The expansible spring 12 is supported on a pin 11 having a collar 11¹. One end of the spring presses 105 under tension against the side portion 2 of the body and its opposite end presses against the upturned portion 8 of the sliding mem-

ber forcing the latch to its normal yieldingly locked position as shown in Figure 1. A strike B is used in association with the latch for locking purposes.

5 A U-shaped cam member 13 is preferably provided with an elongated aperture 14 formed in one of its members and a square aperture 15 in the other spaced apart member as shown in Figures 7 and 8. A shaft 10 16 is provided with a collar 17 formed in contact with the body portion of the body. A portion 18 forms a journal to fit the aperture 8 formed in the body portion 1 of the body and the end 19 is formed to fit the aperture 14 formed in the U-shaped cam member to provide means for imparting movement thereto. The lever 20, or the shaft 21 can be operated in either direction. To hold the shaft, sliding latch member and 15 20 U-shaped cam member in assembled position, the surplus stock of the end of the lever is riveted over a portion of the cam member as shown at 22 in Figure 4.

The lever 20 is constructed of a sheet metal member 23 which is encased by a sheet metal cover 24 which is beaded around the member 23 to fasten and hold same in close contact with the part 23. The sheet metal member 23 is riveted to the shaft 16 at its 25 30 free end or otherwise fastened thereto, in any conventional manner.

When the parts are assembled as described and the lever 20 is manipulated in either direction the ends of the cams 25 or 26 are 35 forced in contact with the upturned portion 8 of the sliding latch member imparting movement to the sliding member 7, thereby retracting the latch 10 on a plane with or slightly under the plane of the side 2¹ permitting the door to be opened. When the lever 20 is released the tension of the spring 12 forces the sliding latch member to the end of its outward position shown in Figures 1 and 2, thereby yieldingly locking the 40 45 door with the aid of the conventional strike or the like as shown at B. The same movement of the latch member and its associated mechanism is obtained, when the U-shaped cam member is actuated by the shaft 21, upon which an ordinary knob (not shown) is mounted and secured.

In Figure 9 attention is called to the fact that the lever 20 is shown moved in opposite directions. Movement of the lever 20 in either direction retracts the latch or positions same in yielding unlocked position as shown by the dotted lines on said figure. When the lever 20 is released from the grasp

of the operator the latch is immediately returned to its yielding locked position as shown in full lines by the expandible spring 12.

It will be observed that all of the parts, except the shaft 21 are made of polished sheet metal or the like and pressed to form so that each and all of the parts have smooth surfaces interiorly and exteriorly, providing means of finishing the parts smoothly when compared with ordinary rough surfaces of castings or the like.

It will also be observed that in attaching the shaft 21 to the U-shaped cam member instead of to the knob or member, which ordinarily passes through the body and into the knob or lever, that the length of the shaft 21 is shortened and material in making the shaft is saved. The shaft 21 is held in place by a cotter pin 27 or the like. The rib 5 provides a stop for the sliding latch member 7.

I claim:

1. A latch mechanism, a hollow body providing a casing, a sliding latch member guided in the casing and including an upstanding rear wall, means carried by the casing and bearing against said wall to normally project the latch in operative position, an operating element rotatably mounted in the casing and projecting through a slot in the latch member, a cam member secured to said operating member and including a U-shaped section, the inner portion of which is secured to the operating member and presents an edge to bear against the upstanding rear wall of the latch member to operate said member, the outer portion of the cam member being arranged in superimposed spaced relation to the inner portion and providing a means for connecting a second operating member thereto for the operation of the latch member.

2. In a latch mechanism formed of sheet metal, a casing, a sliding bolt having portions thereof bent at right angles to the body portion, a combined cam and connecting member bent substantially U-shaped and which provides means for connecting a shaft to the cam portion and another shaft to the connecting member thereof in spaced apart relation to each other, whereby means are provided to impart movement to the cam and bolt in either direction and from both sides of the casing as described and set forth.

In testimony whereof I affix my signature.

HARLEY BROOMHALL.
